ALBERT H. DE VOE, OF WESTFIELD, NEW JERSEY, ASSIGNOR TO THE SINGER MANUFACTURING COMPANY, A CORPORATION OF NEW JERSEY.

DIFFERENTIAL FEEDING MECHANISM FOR SEWING-MACHINES.

1,317,006.

Specification of Letters Patent. Patented Sept. 23, 1919.

Original application filed March 21, 1916, Serial No. 85,535. Divided and this application filed April 5, 1917. Serial No. 159,888.

To all whom it may concern:

Be it known that I, ALBERT H. DE VOE, a citizen of the United States, residing at Westfield, in the county of Union and State 5 of New Jersey, have invented certain new and useful Improvements in Differential Feeding Mechanisms for Sewing-Machines, of which the following is a specification, reference being had therein to the accompanying drawings.

This invention relates to differential feeding mechanism for sewing machines and more particularly to differential feeding mechanism of the four-motion type wherein 15 two feed-dogs are commonly given equal feed-and-return movements and differential rising-and-falling movements for purposes of fulling in or stretching fabric before it is stitched.

20 The invention has for an object to provide a simplified and improved construction of differential feeding mechanism comprising but few operative parts and capable of quiet and efficient operation at high speed.

25 More specifically, the invention has for an object to provide a simplified differential feeding mechanism adapted for use in a sewing machine having a cylindrical work-supporting arm and so constructed as to take 30 up but little space within the work-supporting arm of such machine.

According to the present improvement which, in the present instance, is embodied in a cylinder bed machine of the feed-off-the-arm type, two feed-dog-carrying bars or levers are pivotally connected together to partake of equal feed-and-return movements and differential rising-and-falling movements. In the present embodiment of 40 the invention, the lever which carries the forwardly disposed or auxiliary feed-dog is fulcrumed between its ends upon a movable pin carried by a pair of short, up-standing links whose lower ends are supported upon 45 a fixed pin. Rocking and bodily endwise movements are imparted to this lever by a link-and-lever connection with a pair of angularly spaced driving eccentrics fixed to the main-shaft. As this lever serves to actuate both feed-dogs it may be termed the primary lever.

The other feed-dog-carrying bar or lever carries the main or stitch-length defining feed-dog and may be referred to as the sec-

ondary lever since it derives its rising-and-falling movements from the primary lever through an intermediate element or differentiator pivoted to the primary feed-lever and anchored to the frame by means of a link. In the present instance, an adjustable pin carried by and shiftable lengthwise of the secondary lever enters a slot in the differentiator which acts to raise and lower the secondary lever relatively to the primary lever and differentiate the rising-and-falling movements of said levers during the feeding movement.

In the accompanying drawings Figure 1 is a side elevation of a feed-off-the-arm sewing machine head with the work-arm in 70 section to show the improved feeding mechanism. Fig. 2 is a plan view of the same. Fig. 3 is a fragmentary longitudinal section through the work-arm showing a portion of the feeding mechanism in plan and Fig. 4 75 is a detail perspective view of the differentiator.

In the particular embodiment of the invention illustrated, the machine frame comprises a transversely extending body-portion 80 1 which is adapted to be supported in the manner disclosed in my copending application Serial No. 85,535, filed March 21, 1916, of which this application is a division. The ends of the body-portion 1 are fitted with 85 bearings 2 and 3 for the main-shaft 4 which carries the feed actuating eccentrics 5 and 6 and is extended at one end beyond the bearing 3 to support the hand-wheel 7.

Extending downwardly and rearwardly 90 from the body-portion 1 is a hollow L-shaped work-arm 8 comprising a substantially vertical portion 9 and a substantially horizontal portion 10 supporting a throat-plate 11. Disposed directly above the free end of the 95 work-arm 8 is the head 12 having a laterally projecting boss 13 connected to the body-portion 1 by a channeled bracket-arm 14, disposed above and at one side of the plane of the work-arm, as shown in Fig. 2.

The sewing needles 15 are arranged in a line inclined to the direction of feed and are supported on the needle-bar 16 which is reciprocated in bearing bushings 17 received in suitable sockets in the head 12 and held in 105 place therein by set-screws 18. A split collar 19 surrounds the needle-bar and is clamped thereon by the screw 20. This

collar is connected by means of the usual link and crank pin (not shown) to the crank-disk 21 formed by the flat face of the bevel-gear 22 mounted on one end of a short shaft 23 journaled in the boss 13. A collar 24 secured to the other end of the shaft 23 by a set screw 25 coöperates with the bevel-gear 22 to hold the shaft 23 in place. Meshing with the bevel-gear 22 is a similar gear 26 carried by one end of the downwardly inclined shaft 27 journaled in bearings 28, 29. The lower forward end of shaft 27 projects into the hollow housing or body-portion 1 and carries a bevel-gear 30 which meshes with a driving gear 31 secured to the main-shaft 4 of the machine.

The presser-foot 32 is pivoted at 33 to a shank 34 carried by the presser-bar 35 mounted behind the needle-bar 16. The usual spring 36 and lifting lever 37 are employed to lower and raise the foot.

Coöperating with the needles 15 are two thread-carrying loopers 38 secured to a looper-support 39 mounted upon one end of the rocking and endwise movable looper-shaft 40 extending within and lengthwise of the horizontal portion 10 of the work-arm. The specific construction of the mechanism for imparting operative movements 30 to the looper-shaft is fully disclosed in my said copending application and need not be referred to herein since it forms no part of the present improvement.

In the specific embodiment of the invention illustrated the differential feeding mechanism comprises the main actuating or primary lever 41 mounted for rocking and endwise movements. To permit these movements the lever is supported between its ends on a pin 42 carried by two, short, up-standing links 43, one at each side of the lever 41, as shown in Fig. 3. The links 43 are mounted on a horizontal pin 44 extending across and within the hollow work-arm and supported by the side wall portions of said work-arm. The end of the lever 41 remote from the stitching point is curved upwardly and connected by a screw-pin 45 to a pitman 46 whose upper end is provided with an eccentric strap 47 which embraces the operating eccentric 5 on the main-shaft. Secured to the other end of lever 41 by a screw 48 is an auxiliary feed-dog 49 which in the present instance is adapted to full in the work and is disposed under the forward portion of the operative surface of the presser-foot. Endwise movements are imparted to the lever 41 by means of a link 50 secured thereto by a screw-pin 51 and deriving movements from a pin 52 adjustably mounted in a slotted arm 53 carried by one end of a sleeve 54 surrounding and supported by the pin 55. Extending laterally from the other end of sleeve 54 is an arm 56 connected to the lower end of pit-

man 57 whose upper end is provided with an eccentric strap 58 embracing the eccentric 6 on the main-shaft.

The main feed-dog 59 is secured by a screw 60 to a secondary lever 61 disposed at one side of the primary lever 41 and including an enlarged and offset end portion 62 which is undercut so that it may straddle the lever 41 to which it is connected by a pivot pin 63. Referring to Fig. 3, the side face of the secondary lever 61 adjacent the primary lever 41 is recessed at 64 to receive a small plate 65 carrying at one end a pin 66 which projects laterally from the side face of the lever 61 adjacent the lever 41. The plate 65 is adjustable lengthwise of the lever 61 and is held in adjusted position within the recess 64 by a screw 67. Positioned between the feed levers is a differentiator 68 preferably in the form of a flattened member which has a pin 69 projecting from the upper corner of one side face thereof as shown in Fig. 4. This pin 69 enters a hole in the lever 41 which serves to support the differentiator 68 and impart actuating movements thereto. The lower end of member 68 is anchored to the fixed pin 44 by a short link 70 which serves to control the movement of the differentiator 68. It will be seen that when the primary lever 41 is moved forwardly the member 68 will be tilted forwardly in somewhat the same manner as the links 43.

In the present instance, a rectangular groove 71 is cut in that side face of the differentiator 68 which lies adjacent the adjustable plate 65, as shown in Figs. 3 and 4. This groove 71 is adapted to receive the adjustable pin 66 and is so cut relatively to the pin 69 that, when the parts are in assembled relation, the pin 66 may be adjusted to a position in axial alinement with the pin 69. When pin 66 is so adjusted there will be no movement of the levers 41 and 61, relatively to each other, when the machine is operated. However, by adjusting the pin 66 to the position shown in Figs. 1 and 3, it is evident that, with the parts in the position shown in Fig. 1, as the main-shaft is rotated in the direction of the arrow, the primary lever 41 will be moved in the direction of feed by the rising pitman 57 acting through the bell-crank 56, 53 and link 50, and this movement of lever 41 will act through pin 69 to tilt the differentiator 68 and cause the groove 71 therein to be inclined downwardly from the pin 69. Consequently the pin 66 will be lowered relatively to the pin 69 and the main or stitch-length defining feed-dog 59 will be lowered relatively to the auxiliary feed-dog 49.

As a result of this differential movement, the stitch-length or rearward feed-dog 59 will drop away from the work and cease its feeding action sooner than the auxiliary

feed-dog 49. In this construction a single line of connections lengthwise of the horizontal portion 10 of the work-arm is utilized to impart motion to the differentially acting feed-dogs. In other words the motions caused by eccentrics 5 and 6 are transmitted to the feed-dogs 49 and 59 through a single connecting element, to wit, the primary feed-lever 41. The said lever 41 may be considered as divided by an imaginary transverse vertical plane between the pivots 51 and 63 into two lengthwise extended portions, to one of which portions the actuating links 46 and 50 are connected and the other of which portions supports the main and auxiliary feed-dogs. Thus the main and auxiliary feed-dogs and the feed-differentiating mechanism are disposed wholly forwardly of the actuating means for the feed-lever 41, and the use of main and auxiliary feed-bars extending substantially the full length of the work-arm, as heretofore, is avoided. There is thus no overlapping within the work-arm of the actuating connections for the feed-lever 41 and the feed-differentiating connections, and the space required by the feeding mechanism is accordingly reduced to a minimum. While I have shown the pivot 51 as disposed comparatively near to the pivot 63, it is obvious that its position upon the bar 41 is immaterial, in the broader aspects of the invention. Adjustment of the pin 52 in the slotted arm 53 will vary the effective throw of both feed-dogs without perceptibly altering their relative differential feeding action, whereas, adjustment of the pin 66, changes the effective throw of only one feed-dog, *i. e.*, the stitch-length feed-dog 59.

While I have shown and described in detail a specific embodiment of the invention particularly adapted for use with cylinder-bed sewing machines it is to be understood that the embodiment illustrated is obviously susceptible of material modification both in the form and arrangement of the various parts to meet the requirements of the particular use to which the invention is to be put or, in other words, to adapt the invention to other well known types of sewing machines. The invention is not, therefore, to be considered as limited to the exact form illustrated.

Having thus set forth the nature of the invention, what I claim herein is:—

1. Differential feeding mechanism for sewing machines comprising a main-shaft, auxiliary and main feed-dogs, pivotally connected primary and secondary levers supporting said feed-dogs, respectively, means connected to the main-shaft for imparting rising-and-falling and endwise feeding movements to said levers, and means whereby endwise movements of said primary lever are utilized to differentiate the rising-and-

falling movements of one of said levers relatively to the other.

2. Differential feeding mechanism for sewing machines comprising a rocking and endwise movable primary lever, a first feed-dog carried thereby, a secondary lever, a second feed-dog mounted thereon, and means comprising a differentiator carried by said primary lever and movable relatively to both of said levers for imparting differential movements to said secondary lever relatively to said primary lever, whereby differential feeding actions are imparted to said feed-dogs.

3. Differential feeding mechanism for sewing machines comprising a supporting frame, a primary lever, a secondary lever pivoted to said primary lever, operative connections between said levers including a differentiator pivoted to said primary lever, an anchorage between said differentiator and a fixed part of the machine, and an adjustable connection between said secondary lever and said differentiator for varying the differential feeding action of the mechanism.

4. Differential feeding mechanism for sewing machines comprising a supporting frame, a primary lever, a movable fulcrum therefor, a secondary lever pivoted to said primary lever, actuating connections between said levers including a slotted differentiator pivoted to said primary lever, a link connecting said differentiator to a fixed part of the machine, and a pin adjustably mounted on said secondary lever and extending into said slot for varying the differential feeding action of the mechanism.

5. Differential feeding mechanism for sewing machines, comprising a rocking and endwise movable primary lever carrying a feed-dog, actuating means therefor, a secondary lever carrying another feed-dog, and means comprising a differentiator carried by said primary lever and movable relatively to said secondary lever for imparting differential movements to said secondary lever relatively to said primary lever, whereby differential feeding actions are imparted to said feed-dogs.

6. Differential feeding mechanism for sewing machines comprising, in combination, primary and secondary feed-levers, feed-dogs carried by said levers, means for imparting feed-and-return movements to said levers, and means for imparting differential rising-and-falling movements to said levers, said last mentioned means including a differentiator pivotally connected to one feed-lever, controlling means for said differentiator, and a pivotal connection between said differentiator and the other feed-lever.

7. Differential feeding mechanism for sewing machines comprising, in combination, pivotally mounted primary and secondary feed-levers, means for imparting

- simultaneous bodily movements to said feed-levers, means for oscillating one of said feed-levers about its pivot, and connections between said feed-levers including a differentiating lever for converting bodily movements of one feed-lever into oscillatory movements of the other feed-lever about its pivot. 5
8. Differential feeding mechanism for sewing machines comprising, in combination, primary and secondary feed levers disposed adjacent each other, means for imparting endwise feeding movements to said levers, means for imparting rising-and-falling movements to said primary lever, means whereby the rising-and-falling movements imparted to the primary lever are transmitted to the secondary feed-lever, said means including connections whereby the endwise feeding movements of said primary lever are caused to differentiate the rising-and-falling movements of the secondary lever relatively to the primary lever. 10
9. Differential feeding mechanism for sewing machines comprising, in combination, primary and secondary feed-levers disposed adjacent each other, means for imparting endwise feeding movements to said levers, means for imparting rising-and-falling movements to said primary lever, means whereby the rising-and-falling movements imparted to the primary lever are transmitted to the secondary feed-lever, said means including a differentiating lever pivoted to one of said feed-levers and connected to the other lever, and a fulcrum connection between said differentiating lever and the frame, whereby the endwise feeding movements of said primary lever are caused to differentiate the rising-and-falling movements of the secondary lever relatively to the primary lever. 15
10. In a sewing machine, in combination, a supporting frame including a hollow work-arm, stitch-forming mechanism incorporated in said frame, differential feeding mechanism disposed within said work-arm and including two work-engaging members, means for imparting operative differential feeding movements to said members, said means including a single member disposed lengthwise of said arm through which motion is transmitted from the main shaft to both work-engaging members. 20
11. Differential feeding mechanism for sewing machines comprising auxiliary and stitch-length defining feed-dogs, primary and secondary levers supporting said feed-dogs, means for imparting rising-and-falling and substantially equal endwise feeding movements to said levers, said means including devices for converting endwise movements of one of said levers into rising-and-falling movements of the other lever relatively to said one of said levers. 25
12. Differential feeding mechanism for sewing machines comprising, in combination, a lever mounted for rocking and endwise movements, means connected to one portion along the length of said lever for imparting operative movements thereto, auxiliary and main feed-dogs connected with another distinct portion of said lever, and means whereby the operative movements of said lever are utilized to impart differential rising-and-falling movements to said feed-dogs. 70
13. Differential feeding mechanism for sewing machines comprising, in combination, a lever mounted for rocking and endwise movements, actuating means connected to one lengthwise extending portion of said lever for imparting said movements thereto, auxiliary and main feed-dogs operatively supported by a forwardly disposed portion of said lever, and connections wholly forward of said actuating means whereby the operative movements of said lever are utilized to impart differential feeding actions to said feed-dogs. 75
14. Differential feeding mechanism for sewing machines comprising, in combination, a main-shaft, a primary lever having a movable fulcrum between its ends, an auxiliary feed-dog carried by said primary lever, a secondary lever connected with said primary lever and carrying a stitch-length defining feed-dog, and means carried by said primary lever between its fulcrum and the auxiliary feed-dog for imparting differential movements to said secondary lever. 80
15. Feeding mechanism for sewing machines comprising, in combination, a pair of feed-bars, main and auxiliary feed-dogs carried by said feed-bars, and actuating devices for imparting equal feed-and-return and differential rising-and-falling movements to said feed-bars, said actuating devices including a differentiator for converting feed-and-return components of motion of one of said bars into rising-and-falling components of motion of the other of said bars. 85
16. Feeding mechanism for sewing machines comprising in combination, a frame, a pair of feed-dogs, actuating mechanism incorporated in said frame for imparting substantially equal feed-and-return and differential rising-and-falling movements to said feed-dogs, said actuating mechanism including a pair of feed-bars and a differentiator movable relatively to said feed-bars and deriving its movement from one of said feed-bars for producing rising-and-falling movements of the other feed-bar relatively to said first mentioned feed-bar. 90
17. Differential feeding mechanism for sewing machines, comprising, a frame, a primary feed-bar carrying a first feed-dog, actuating means therefor, a second feed-dog, a carrier therefor mounted upon said 100
- 105
- 110
- 115
- 120
- 125
- 130

- feed-bar for rising-and-falling movements, and an anchorage between said carrier and the frame independent of the actuating means for the primary feed-bar, said anchorage including a link pivoted at one end to the frame.
18. Differential feeding mechanism for sewing machines comprising, in combination, primary and secondary feed-dogs, primary and secondary levers carrying said feed-dogs and pivotally connected together for relative rising-and-falling movements, actuating mechanism for imparting operative movements to said primary lever, and anchoring means pivotally connected to said secondary lever and independent of said actuating mechanism for connecting to the frame a point on the secondary lever spaced from the pivotal connection between said levers.
19. Differential feeding mechanism for sewing machines comprising, in combination, a main feed-bar, a forwardly disposed feed-dog carried thereby, a stitch-length-defining feed-dog, an auxiliary feed-bar carrying the latter feed-dog and pivoted to said main feed-bar for rising-and-falling movements relatively thereto, actuating means for imparting rising-and-falling and feed-and-return movements to the main feed-bar, and means independent of said actuating means for differentiating the rising-and-falling movements of said feed-bars.
20. Differential feeding mechanism for sewing machines comprising, in combination, primary and secondary feed-dogs carried thereby, means for imparting endwise feeding movements of substantially equal amplitude to said levers, and means for imparting rising-and-falling movements to said levers including differentiating means for transmitting the rising-and-falling movements of one lever to the other.
21. Differential feeding mechanism for sewing machines comprising, in combination, a frame, a feed-bar, two feed-dogs carried thereby for differential rising-and-falling movements, means for actuating said feed-bar, and a differentiator distinct from the actuating means for said feed-bar and movable relatively to said feed-dogs for differentiating their rising-and-falling movements.
22. Differential feeding mechanism for sewing machines comprising, a frame, a primary feed-bar carrying a first feed-dog, actuating means therefor, a secondary feed-bar pivotally connected to said primary feed-bar and carrying a second feed-dog, and a pivoted link connection between said secondary feed-bar and the frame independent of the actuating means for the primary feed-bar, said link-connection being arranged to swing in the plane of the work-engaging movement of the feed-dog.

In testimony whereof, I have signed my name to this specification.

ALBERT H. DE VOE.
